GIRDLE

Alfred Jacobs and Joseph Ciringione, New York,
N. Y., assignors to The Poisefair Company, Inc.,
New York, N. Y.

Application August 23, 1939, Serial No. 291,565

2 Claims. (Cl. 2—43)

This invention relates to girdles and deals more particularly with garments of like character formed with a crotch.

The incorporation of straps, leg pieces, trunk 5 hose and similar lower extensions into foundation and surgical garments, is at present well known. However, these earlier structures do not meet the conditions required in a garment of modern design. Because of the increased athletic activities of the female and the tendency 10 towards simplification and lightening of her outer garments, it is essential that her girdle or foundation garment be of neat and trim fit and appearance, and that it maintain its position on the body with little or no restriction to freedom of movement.

In many essentials, the modern girdle incorporates these desirable features and this invention seeks to further improve such garments by 20 incorporating therein a crotch portion designed to suit modern needs and conditions.

More particularly, the invention deals with a girdle formed with an elastic body, the front and back panels of which are stretchable only in 25 the length of the garment, and provided with a crotch portion formed of leg-engaging members stretchable transversely to the stretch of said front and back panels.

The invention also contemplates the provision 30 of a novel crotch for a garment of the character indicated, wherein at the front, the leg-engaging portions forming the crotch are joined to each other by means of a seam forming an extension of a central seam in the front panel of the garment.

Another feature of the invention resides in the reinforcing members provided at the crotch to render the garment longer wearing.

With the foregoing and many other objects, features, and advantages in mind, the invention may be more readily realized from perusal of the accompanying drawing illustrating a garment as at present conceived and incorporating the features of the invention. The following 45 specification, based on the drawing, more fully sets forth the design and details of the invention.

In the drawing:

Fig. 1 is a front view of a girdle made in accordance with the invention as it appears on the human form.

Fig. 2 is a rear view thereof in flat condition.

Fig. 3 is a flat view in pattern form of the essential elements of the present invention.

In that embodiment of the invention here illustrated, the girdle is preferably provided with

side portions 5 and the front and rear panels respectively 6 and 7.

For a clearer understanding of the invention, the elements of the girdle are lined to indicate the direction of stretch. Thus, it may be seen 5 that the sides 5 are preferably made of a material having stretch both vertically and horizontally and that the panels 6 and 7 are preferably stretchable in a substantially vertical direction.

In order to have the stretch in the front panel in the proper direction, said panel is preferably formed of two complementary parts 6a and 6b, united by a seam 8 at the center of said panel. As best seen in Fig. 3, the direction of stretch of 15 these parts are at a slight angle to each other along said seam but predominantly vertical as shown in Fig. 1. The elasticity of the front panel is thus better controlled than should said panel be of one piece with the stretch vertical. 20

In accordance with the invention, the adjacent portions of the bottom edges of the panel parts 6a and 6b are preferably angularly cut as at 9. In a somewhat similar manner the back panel 7, at its bottom edge, is formed with the 25 crescent-shaped notch 10 having the substantially straight edges 11. Thus the front and back panels are each formed with a substantially V-shaped notch at the central lower edge thereof.

The crotch as herein contemplated, comprises 30 the crotch members 12 each having a substantially straight lateral outer edge 13 and formed with a curved lateral inner edge 14. Each crotch member is formed with a relatively long front edge 15 and a relatively short back edge 12, the 35 former being stitched to the respective edge 9 of the front panel member 6a and 6b and the latter to the respective edges 11 of the back panel.

The stretch of the crotch members 12 is in the 40 length of said members but at an angle, or transverse to the stretch of the panels 6 and 7, as illustrated.

It is preferred to form each crotch member with a slightly angled edge 17 between the curved edge 14 and the inner end of the front edge 15 and to join said edges 17 by means of a seam. This seam, on the garment, forms a lower extension 45 of the seam 8 between the panel parts 6a and 6b.

The crotch thus formed, in effect, converts 50 the girdle into a "panty" garment which in addition to serving the normal functions of a girdle, also serve to confine such portions of the thighs, in certain instances, to obviate the use of other undergarments. The opening 18 formed in the 55

crotch between the curved edges 14 adds to the comfort and convenience of the garment.

It will be noted that the crotch portions 12 form leg bands which, together with the lower portions of the girdle, confine the thighs of the wearer to maintain the garment in position on the body.

It is desired that the stretch of the component parts of the girdle and crotch not be transmitted to each other. To obviate the transmission of stretch and to reinforce the seams, inelastic tapes or other suitable means such as shown at 19 may be stitched to the various seams. These tapes are preferably placed along the seams between the edges 9 and 15, at the seam between the edges 17, and at the seam between the edges 11 and 16.

From the foregoing it may be seen that a garment has been provided which carries out the objects of the invention. It is also evident that many immaterial changes within the spirit and scope of the invention as claimed, may be made by those skilled in the art. It is intended, therefore, that the claims not be limited to the specific details of the instant disclosure.

What is claimed as new and desired to secure by Letters Patent, is:

1. In a garment of the character described, a front and a back panel each stretchable in the length of the garment, said front panel being formed of two members joined by a longitudinal central seam, and a crotch for engaging the inner thigh of each leg of the wearer of the garment, said crotch comprising two portions stretchable in a direction transverse to the stretch of said panels, the front ends of said crotch portions being stitched to each other for a portion of their length, the seam thus formed being an extension of the mentioned seam in the front panel. 5

2. In a garment of the character described, a front and a back panel, the lower edge of each panel at the center thereof being formed with a crescent-shaped notch, and a crotch on said garment, said crotch comprising two members having one end of each stitched to the edge of the crescent-shaped notch in the back panel and in spaced relation to each other and having the other end of each stitched to the edge of the crescent-shaped notch in the front panel, said latter ends being stitched to each other for a portion of the length of said crotch members. 15 20
